UNITED STATES PATENT OFFICE.

ANTHONY P. KELLER AND ALBERT M. BEHM, OF TIFFIN, OHIO.

ACETYLENE-GAS GENERATOR.

SPECIFICATION forming part of Letters Patent No. 660,514, dated October 23, 1900.

Application filed February 12, 1900. Serial No. 4,956. (No model.)

To all whom it may concern:

Be it known that we, ANTHONY P. KELLER and ALBERT M. BEHM, citizens of the United States, residing at Tiffin, in the county of Seneca and State of Ohio, have invented certain new and useful Improvements in Acetylene-Gas-Generating Machines, of which the following is a specification.

In the statement of our invention in acetylene-gas machines the following description, read in connection with the accompanying drawings, will enable any one skilled in the art to which our invention relates to understand its nature and to practice it in the form in which we prefer to employ it; but it will be understood that our invention is not limited to the precise form and construction of the several operating parts herein illustrated and described.

In our machine for generating gas from calcium carbid there are features and devices involving novelty of construction, of combination for automatically regulating and supplying water to a pair of gas-generators, for cooling the gas in its flow to the gas-holder or float, for automatically ventilating the generators by opening communication therewith to the outer air when they become exhausted of the gas-producing properties of the calcium carbid and before being recharged, and for automatically diverting the gas from the gas-holder into an air or waste pipe as a means of safety against undue pressure and volume of gas in the holder; and the invention embodies provision whereby through connections with the float or gas-holder its movements are caused to regulate and control a valve for supplying the water to the generators, a valve for diverting the flow of the gas from the gas-holder to a waste-pipe, and valves whereby the exhausted generators are ventilated during the operation of the machine, these several operations of the valves being effected at the proper times to render the working of the machine continuous with the highest degree of efficiency and safety.

Referring to the drawings, Figure 1 represents in side view a gas-generating machine embodying our invention, wherein is seen in vertical section a gas-generating tank and a gas-purifying tank, from which the gas is

delivered into the float or holder. Fig. 2 is a front view of the machine, the gas-generators being removed, showing their connecting outflow-pipes q q in section, by which the gas is delivered from the generators into the cooling-tank F, shown by dotted lines within the water-cylinder in Fig. 1. Fig. 3 is a side view, enlarged, of the safety-valve p' , the rod h^2 , by which the valve is automatically opened by the raising of the float, and the weighted arm g' for closing the valve, as it is seen in Figs. 1 and 2, the opening of this safety-valve only occurring when the float has reached its maximum height, whereby to prevent the further inflow of gas into the float and the cutting off of the water-supply. Fig. 4 shows the same valve in top view and its actuating parts. Fig. 5, Sheet 2, shows, enlarged, in side view the ventilator-pipe, its controlling plug-valve i' , and the connections for actuating it, as seen in Figs. 1 and 2. Fig. 6 shows in front view the ventilating-valves i' i' , the pipes controlled thereby, and the actuating connections for said valves, the pipes q q , connecting the generators, being shown in section. Fig. 7 shows in top view the ventilating-valve i' and its operating armed connection. Fig. 8 shows in side and end views the armed shaft b' and its pins by which the ventilating-valve is actuated. Fig. 9 shows in vertical section the lower part of the water-cylinder and inside elevation therein the gas-cooler. Fig. 10 shows the gas-cooler in top view, and Fig. 11 shows the gas-cooler in vertical section and its connected gas-purifier in side view. Fig. 12, Sheet 3, shows, enlarged, the water-supply pipes, the water-transfer spout, and the connections by which the valve f is actuated for controlling the supply of water to the generators, as seen in Fig. 2. Fig. 13 shows the same parts taken at right angles to Fig. 12. Fig. 14 shows in top, side, and end views the water-transfer spout; and Fig. 15 shows the rock-shaft and its pins, in side and end views, by which the water-transfer spout is tilted to change the flow of water. Fig. 16 shows in horizontal section on the line 4 4 of Fig. 1 the water-cylinder, the gas-generators, the gas-cooler, and the gas-purifier and their connections. Fig. 17 is a detail showing the safety-valve and the pipes connecting it with the purifier and the ventilating-pipe; and Fig.

18 shows the complete machine in perspective, with the two gas-generators and their connections.

The front of the machine will be considered 5 that side at which the gas-generators are set.

The gasometer consists of the fixed open-top cylinder D, which is maintained filled with water to the dotted line 20, Fig. 1, and the gas-holder D', floated and sealed therein 10 to retain the gas therein and which has a rising-and-falling movement, according to the pressure of the gas between the top of the float and the surface of the water, in the usual manner for supplying the burners, by a dividing-pipe 21, opening into the chamber of the float, passing through the water therein, and out at the bottom, at v, to the burners, as seen in dotted lines in Fig. 1 and in full lines in Figs. 9 and 16.

20 Two generators A A' are provided for separate and alternate use, each having a separate and independent carbid-holding bucket or vessel B, supplied with water by separate and independent pipes E E', each rising vertically at the sides of the generators and some distance above and entering the generator by a water-seal trap connection. (Seen in Figs. 1 and 18.) Each generator has a lid c, which is clamped in place by a pivoted yoke d and a 25 clamp-screw e. The bucket for containing the calcium carbid is of less size than and sits within the generator and has a fixed central perforated pipe b, having a funnel a at its top and a circular plate b' at its bottom

30 of less diameter than the bucket and raised a little from the bottom. Each water-supplying pipe is bent to form a loop-trap, which opens into the funnel and when filled with water prevents the escape of the gas from the 35 generator through the open water-supply pipe, but allows the free flow of the water into the generator. The central perforated pipe b allows the water to pass through its walls and which also passes under its bottom

40 plate b' into the calcium carbid, and the gas generated thereby fills the tank A and passes therefrom through the downtake-pipe q' and pipes q² s into a cooler F, submerged in the water-cylinder. Preferably this cooler, as 45 shown, is a narrow oblong tank, having a height about half that of the water-sealing cylinder, and is divided by a vertical partition s², Figs. 11 and 16, into two compartments communicating at the top, whereby the gas

50 entering at the bottom by the perforated pipe s' is caused to pass upward and downward over the partition s² in contact with the long side walls, which thereby radiate all undue heat from the gas before it enters the purifier G. The purifier consists of a tank filled with cotton. (Not shown.) The gas leaving the cooler at its bottom by the pipe x² enters the bottom of the purifier and leaves it at the top by the pipe t, which, entering the wall at 55 the bottom of the water-cylinder, extends upward by the branch t' and opens into the gas-holder above the level 20 of the water, as

seen in dotted lines in Fig. 1. The gas entering the cooler is separated and distributed therein in streams by a perforated pipe s', 70 which forms an extension of the pipe s, thus giving the fullest heat-radiating effect to the gas. The arrangement of the cooler within the water-sealing cylinder and its connection with a purifier external to said cylinder gives 75 the important advantage of cooling the gas before it passes into the purifier for cleaning and drying it before it passes into the holder or float from which the burners are supplied. This arrangement also gives the advantage 80 of a simple construction of cooling-tank seated upon the bottom of the water-cylinder, so as to be entirely submerged, and the advantage of the gas first passing through the submerged tank and again through this body of 85 water by the uptake-pipe l' after it has passed through the external purifier, thereby subjecting the gas to two distinct cooling actions before it enters the supply-chamber of the float, in its passage from which it is again 90 cooled in the downtake-pipe 21, which passes through the body of the water to the bottom of the water-cylinder and thence to the burners by the pipe v, Fig. 1. These three cooling flows of the gas being within the water-cylinder are thus provided by radiating walls and gives compactness to the means which renders effective the cool condition of the gas in the supply-float, which conduces to safety 95 in the accumulation under pressure of dry 100 gas free from foreign material.

The water-supplying pipes terminate in open funnels side by side, and above them is the water-supplying tank C, mounted by a suitable bracket on the upper end of the gas-holding float. Depending from this tank is a tube c², upon which is pivotally mounted a tray or double-ended chute i, adapted to receive and automatically transfer the water alternately from one pipe E to the other in 105 the operation of supplying the water to the generators. This tray or chute is double-ended, and its mounting-pivot l, Fig. 13, is immediately of its length, so that it is free to be tilted to deliver the water alternately into 110 the supply-pipes of the generators. A transverse rod l, immediately fixed to the chute, forms its pivot and has its bearings in lugs depending from a bracket h, fixed to the lower end of the tank-tube. The rocking of 115 this pivot-forming rod tilts the chute to bring its delivering end directly over the generator supply-pipes, as seen in Figs. 2 and 12, so as to deliver the water alternately into these 120 pipes. This water-supply is effected and controlled by the rising and falling of the 125 float or gas-holder by means which I will now describe.

A plug-valve f in the tank-tube has a rod g fixed thereto, which extends to and has a 130 free sliding joint connection h² with the float, so that the rising and falling thereof will cause the arm g to open and close the valve f to control the supply of water. The valve-

rod g has a depending arm p , having somewhat the form of a crank near its valve connection, and is so formed as to have the function of a cam in its swing movements.

5 In the projecting end of the bracket h is horizontally mounted a rock-shaft m at right angles to the pivot of the tilting chute, and at one end of this rock-shaft are fixed diametrically-projecting arms $o o$ of equal length, which terminate in reverse curves, Figs. 15 and 13, which, with the crank cam-arm p , form coacting cam parts, the action of which effects the rocking of the shaft m , which in turn effects the rocking of the pivot-rod l to tilt the chute. The rock-shaft m has diametrically-projecting pins $n n'$, and the pivot-rod l has diametrically-projecting pins $l' l'$, Fig. 14, and the relation of these separate sets of pins is such that when the float lowers the crank cam-arm p of the float connecting-rod g comes in contact with the cam-arms $o o$ on the rock-shaft m and causes thereby said shaft to make one-half of a revolution, bringing one of its pins n or n' in contact with the pins l' or l on the pivot-rod l , thereby causing it to rock and the chute to tilt from one side to the other, thereby changing the flow of water from the generator which has become exhausted into the other generator.

30 It will be understood that it is the decrease of the gas-pressure in the float that causes it to lower and that this decrease of gas-pressure is caused by the exhausting of the gas-producing element of the calcium carbide.

35 For holding the chute in its tilted position a plate-spring 7 , Figs. 12 and 13, fastened to the bracket h , engages a float-recess 8 in the rock-shaft m , Fig. 15, the tension of the spring yielding readily to allow the turning of the chute by the cam actions, as stated, to change the flow of water.

40 That it may be seen at a glance which of the gas-generators are exhausted an indicating-arm k is fixed on the chute-pivot l and stands downpointing to the empty generator, as in Fig. 2, thus giving notice that it should be renewed. For this purpose the indicating-arm k is fixed to the chute-pivot at right angles to the line of the chute, so that the tilting of the latter carries the indicator from one side of the stand-pipes $E E'$ to the other. This indicating-arm extends above the chute and has a weight j , the purpose of which is 45 to hold the chute in its tilted position, and for this purpose, referring to Figs. 2 and 12, the ends of the chute are seen as oblique, so that when tilted they will abut against the under side of the bracket, which will form a stop, and thus the weighted arm will hold the chute against the stop whichever way the chute is tilted. The weight, however, is not sufficient to interfere with the free tilting of the chute by the means described.

50 Preferably the connection of the water-controlling valve-arm g with the float is connected to the rod h^2 at the top of the float, as

in Figs. 1, 2, and 18, and extends down to near the bottom of the water-containing cylinder. This connection of the valve-arm is such that when the float contains little or no gas-pressure it is at its lowest position and the valve f will be open and allow a full flow of water into the generating-pot into which the water-chute is delivering.

75 Referring to Figs. 6 and 16, it will be seen that the gas-supply pipe q from each generator connects with the single pipe s , leading into the cooler, and therefore the gas as generated passes through the pipe q from either generator directly into the cooler by the pipe s .

80 To isolate the exhausted generator, its out-flow-pipe q is provided with a cut-off valve 2 , Figs. 1, 16, and 18. Check-valves rr are also provided in the pipes $q q$, which while allowing the gas to open them to pass freely from the generators to the cooler are to prevent the gas by back pressure passing from the float into the exhausted generator when the cut-off valve 2 is not closed, or from any other cause, such as to open the pipe q to the air, prevent the backflow of the gas from the float check-valves for this purpose being well understood.

95 Provision is made by a safety-valve p' for allowing the gas to escape from the gas-holder in the event of any accident which would cause the generation of more gas than the holder could contain with safety. This provision is an automatic safety-valve p' , fitted in a pipe 9 , Figs. 1, 17, and 18, rising as a branch of the pipe t , leading from the top of the purifier into the water-cylinder and opening into the ventilator-pipe m' , as in Fig. 17. A weighted arm q' , Figs. 1 and 18, connects and extends from the stem of the valve p' and has a crank end 10 , Figs. 3 and 4, which engages the side of the pipe to hold the weighted arm horizontal, with the valve closed. This valve is opened automatically by means of a pin s' , projecting from the lower end of the float depending rod h^2 and in such relation to the said weighted arm that when the float is approaching its highest point by reason of the volume and pressure of the gas therein this rod-pin s' will be brought into engagement with and, lifting thereby the weighted arm q' , open the safety-valve, and thereby cause the gas passing from the purifier to be diverted from the float into the ventilator-pipe m' and relieve the undue pressure in the float. For this purpose the ventilating-pipe is convenient, and its use for the two purposes is a feature of our improvement; but the safety-valve may be on a separate waste-pipe.

100 Provision is made for automatically ventilating the generating-tanks as soon as they become exhausted, thereby clearing them of gas and fumes before recharging them. The means whereby this ventilation is effected consists of branch pipes m^2 , Figs. 2 and 6, rising from the pipes $q q$ between the gen-

erators and the check-valves, Figs. 6 and 16, and connected with a pipe m' , leading outside of the building in which the machine is used, so that each generator can be independently ventilated by causing the fumes to pass from the pipes q up through the branch pipes m^2 thereon, the check-valve r in the pipe of the exhausted generator being closed by the back pressure of the gas from the gas-holder. The opening of the pipe q to the outer air for this purpose is rendered automatic by a plug-valve $i' i'$ in each branch pipe m^2 , which are operated by the following means: A horizontal shaft b is mounted in brackets $c' c'$, fixed on the branch pipes m^2 , and has oppositely-projecting pins $g' g'$, Fig. 8, one for use with and near each valve, while at its end this shaft b' has two oppositely-projecting pins $a' a'$, whereby the shaft is caused to be rotated, as will be presently stated. Connected with the stem of each valve i' is a weighted arm x' , each having a crank end part h' , Figs. 6 and 7, bent to form a sort of cam in its coacting function with the arms g' of the shaft b' . One of these arms stands horizontal and the other stands vertical, and each in its normal position keeps its connected valve closed, as in Figs. 2 and 6. The rotation of the shaft b' causes its arms $g' g'$ to engage the crank ends h' of the weighted arms x' in a way to rotate the valves i' to open them, and this operation is effected as follows:

The depending rod h^2 , besides serving as the means to open and close the water-supplying valve f , serves as the means of connecting and actuating a lever y , Figs. 1 and 2, pivoted to an arm fixed on the vertical branch of the ventilating-pipe m' and having a depending arm x , Figs. 1 and 5, terminating in a crank and having such relation to the pins $a' a'$, Fig. 8, as to engage them in a way to give a half-revolution to the shaft b' . The sliding jointed connection of the lever-arm y with the depending rod h^2 is such as to allow the lever-arm y to rise and fall with said depending arm x and to have a slight Sliding movement in said jointed connection.

When one of the shaft-arms g' is engaged with the valve lever-arm h' to open the valve, the other arm g' is out of action, and when one of the shaft-pins a' is acting on the lever-arm x the other shaft-pin a' is out of action. Looking, therefore, at Figs. 1 and 2, it will be seen that when the gas-holder and its depending rod h^2 are lowered by the use of the gas the lever y will be carried down, bringing its depending arm x in contact with one of the shaft cam-pins a' , giving a half-rotation to the shaft, which will bring one of the shaft-pins g' into engagement with the crank end of the weighted arm x' of one of the valves i' , causing the valve to be opened for the escape of the fumes from the exhausted generator. The exhaustion of the generator will cause the gas-holder to lower to such an extent that the depending cam-arm p of the arm

g will be brought into contact with one of the cam-pins o of the shaft m , causing it to make one-half of a revolution, bringing one of its projecting pins n or n' into contact with one of the pin projections l of the chute-shaft, and thereby cause the chute to be thrown to the opposite side, thus changing the flow of water to the other generator, and the generation of the gas will thus be repeated. The changing of the position of the chute will at the same time throw the weighted indicator over so that it points to the empty generator and holds the chute in its changed position. While the above operation is taking place the lever y is also caused to lower by the lowering of the gas-holder, thus bringing its depending cam-arm x into contact with one of the shaft cam-pins a' , causing the shaft to make one half-revolution, bringing one of its pins g' into contact with the crank-arm h' of the ventilating-valve, throwing it down, so that its weighted arm will rest upon the bracket H , thus opening the valve and allowing the gas and fumes to pass out from the exhausted generator. This ventilating-valve remains open until the generator is recharged, when the valve is closed by the operator raising the weighted arm x' to a vertical position, as in Figs. 2 and 6, in which one of the valve-weighted arms is shown in its thrown-down position. In this way the operation is repeated, and when the other generator is in like manner exhausted the ventilator-shaft will be turned another half-revolution, and thereby cause the second ventilating-valve to be opened to allow the gas and fumes to escape from the second generator.

It is important that while the float depending rod h^2 has the functions of controlling the water-supply valve f and the ventilating-valves $i' i'$ it also has the function of opening the safety-valve p' , and this is effected by a pin s' on the lower end of said rod (when the latter is carried up with the gas-holder to such a height as undue pressure in the gas-holder would cause) being brought in contact with the weighted arm q' and lifting it, thereby opening the safety-valve p' and allowing the gas to pass direct from the generators into the ventilating-pipe m' . This pipe, therefore, while being made to have automatic communication with the generators to carry away the gas and fumes remaining in them after their exhaustion of the gas-producing properties of the calcium carbide is also made to have automatic communication with the generators as a means of diverting the gas as it is being generated from the gas-holder and directing it into an escape-pipe.

In Figs. 1 and 16 are shown hand-valves 2 on the pipes $q' q$ for closing the communication of the pipes with the gas-generators when recharging them, while in Figs. 1, 17, and 18 is seen a valve 3 in the outflow purifier-pipe t for cutting off communication between it and the gas-holder when renewing the cotton filling of the purifier.

In the operation of the machine the gas passes from the generator through the pipe q into the pipe s , thence into the perforated pipe s' of the cooler, and thence into the purifier by the pipe x^3 , from the top of which the gas passes by the downtake-pipe t into the branch pipe t' in the water-cylinder and opens by this uptake t' into the gas-holding chamber. In this flow of the gas the valves 22 are open, the 10 check-valves in their normal closed position, and the valve 3 open and the safety-valve closed. The water-cylinder is filled at 5, and 6 is the draw-off valve, and the generators may be provided with the usual waste-valves. The 15 provision for automatically cutting off the flow of water to the generators being self-acting, under no circumstances can the water continue to be supplied to the generators after the lights are turned out and the gas 20 reaches a pressure to cause the float to rise to its maximum. Then the arm g , rising with the float, will turn the plug-valve f and close the outflow from the water-reservoir.

The provisions for cooling the gas and then 25 purifying it through cotton takes from it all smell, and therefore the lights can be turned down very low without giving off obnoxious fumes.

We claim—

30 1. In a gas-generator of the character described and in combination with a water-cylinder, a gas-holding float sealed therein, a gas-generator and a gas-purifier both external to the water-cylinder, a gas-cooling tank within 35 the latter, and a water-reservoir, with a water-sealed supply-pipe connecting the generator, a gas-pipe connecting the latter with the bottom of the cooling-tank, a perforated pipe s' in the latter forming a continuation of said 40 gas-pipe, the pipe x^3 connecting the bottom of the cooling-tank with the bottom of the purifying-tank, the pipe x^4 connecting the top of the latter with a diving pipe t entering the bottom of the water-cylinder and rising 45 therein by a branch pipe t' opening into the gas-holding float, the gas downtake-pipe 21 and means for supplying water to the generator, substantially as described.

2. In a gas-generator, and in combination 50 with a water-cylinder, a gas-holding float sealed therein, a pair of gas-generators, and means for connecting them with the gas-holding float, a pair of downtake-pipes side by side, open at their upper ends, each entering 55 the gas-generator by a water seal, a water-reservoir having a depending nozzle, a lever g connecting said plug-valve and float and having a depending cam-arm, p , a bracket on the discharge end of the nozzle, a double-ended chute pivoted to said bracket and having oppositely-projecting pins l l' , a shaft m on said bracket at right angles to the tray-pivot adjacent to its pins, and having pins n n' adapted to engage the pivot-pins, and cam- 60 arms o o adapted to be engaged by said cam-arm p , whereby the rising-and-falling movements of the float are caused to control the

water-supply valve and to tilt the chute to deliver into one or the other of the downtake-pipes, in the way and for the purpose stated. 70

3. In a machine for generating acetylene gas, and in combination with a water-cylinder, a gas-holding float sealed therein, and a generator external to the water-tank, a pipe q connecting the generator and the gas-holding float, and having a check-valve r between the tank and the generator, an uptake-pipe m^2 connecting the pipe q between the generator and the check-valve, and open to the air, a plug-valve v in said pipe m^2 , a lever y connecting said valve and having a depending cam-arm x , a rod h^2 connected to and depending from the gas-holding float, and connected to said lever y and means adapted to be engaged by the depending cam-arm x and to 80 engage the said valve, whereby when the gas-producing substance is exhausted, the descent of the gas-holder caused thereby, will open said valve and allow the gas and fumes to pass from the generator to the air as a means 90 of ventilating the generator before renewing the carbid.

4. In a gas-generator and in combination with a water-cylinder, a gas-holding float sealed therein, and a gas-generator external to the water-cylinder, a pipe q connecting the generator and the gas-holding float, of a check-valve to cut off said communication, by the back pressure from the gas-holder, and a pipe m^2 located in said pipe q , between the said 100 check-valve and the generator, and open to the air, a valve controlling said open-air pipe, and means connecting said valve with the gas-holding float, whereby to open the generator, for ventilation to the outer air. 105

5. In a gas-generator and in combination with a water-cylinder, a gas-holding float sealed therein and a gas-generator external to the cylinder, a pipe q connecting the generator and the gas-holding float, a gas-cooling tank within the water-cylinder, a gas-purifying tank external to the latter, and a pipe t connecting the purifying-tank with the water-cylinder, and gas-holding float, with a pipe 9 connecting the pipe t between the purifier 115 and the water-cylinder, and open to the air, a valve p in said pipe 9 and means connecting said valve with the gas-holding float, whereby when the float has reached its maximum height the said valve will be caused to 120 be opened to divert the gas from the gas-holding float, into the open-air pipe to relieve the pressure in the gas-holder.

6. In a gas-generator, and in combination with a water-cylinder, a gas-holder sealed therein 125 and a gas-generator external to the cylinder, a gas-supply pipe connecting the generator and the purifier and the gas-holder, and a pipe 9 external to the water-cylinder connected with the pipe which connects the generator and the purifier and open to the air, a safety-valve p on the open-air pipe, a weighted arm on said valve normally closing it, and the rod h^2 connected to the float and having a pin s' 130

adapted to engage the valve-arm whereby when the gas-holder is at its maximum height the valve is caused to be opened to divert the gas from the gas-holder into the open-air pipe in the way and for the purpose stated.

7. In a gas-generator, and in combination a water-cylinder, a gas-holder sealed therein and a gas-generator external to the cylinder, a gas-supply pipe connecting the generator 10 and the gas-holder, a pipe m^2 between the generator and the cylinder open to the air and connected with the gas-supply pipe, a pipe 9 connecting the open-air pipe external to the cylinder and between it and the pipe m^2 , a 15 plug-valve i' on the latter pipe and means connecting it with the gas-holder whereby the valve is opened on the maximum descent of said gas-holder, a plug-valve p' on the pipe 9 and means whereby said valve is opened on 20 the maximum height of the gas-holder substantially as and for the purpose specified.

8. In a gas-generator, and in combination a water-cylinder, a gas-holder sealed therein and a gas-generator external to the cylinder, 25 a water-reservoir and a pipe delivering water therefrom to the generator, a gas-supply pipe connecting the generator and the gas-holder, a pipe m^2 open to the air arranged to communicate with the gas-pipe for ventilating the 30 generator, a pipe 9 connecting the gas-pipe and the open-air pipe for diverting the gas from the gas-holder, a plug-valve controlling the water-supply, a plug-valve in the ventilating-pipe, a plug-valve in the gas-diverting 35 pipe, and means including suitable connections whereby the said several valves are operated by the raising and lowering of the gas-holder in the way and for the purpose stated.

9. In a gas-generator, and in combination

a water-cylinder, a gas-holder sealed therein 40 and a gas-generator external to the cylinder, a water-reservoir and a pipe delivering water therefrom to the generator, a gas-supply pipe connecting the generator and the gas-holder, a pipe open to the air arranged to communicate 45 with the gas-pipe for ventilating the generator, a pipe connecting the gas-pipe and the open-air pipe for diverting the gas from the gas-holder, a plug-valve controlling the water-supply, a plug-valve in the ventilating-pipe, a plug-valve in the gas-diverting pipe, a rod connecting to and depending from the gas-holder and means including suitable connections 50 whereby the said several valves are operated by the rising-and-falling movements 55 of the depending rod of the gas-holder in the way and for the purpose stated.

10. In a gas-generator of the character described, and in combination a water-generator, a gas-holder sealed therein and a gas-generator external to the cylinder, a water-reservoir and a pipe delivering water therefrom to the generator, a gas-supply pipe connecting the generator and the holder, a check-valve in said pipe, a pipe open to the air arranged to communicate with the gas-pipe between the check-valve and the generator for 60 ventilating the latter, a cut-off valve in the gas-pipe between the generator and the ventilating-pipe, a valve in the ventilator-pipe, 65 and means including connections with the gas-holder whereby the ventilation is effected and controlled by its movements.
